ARTHUR J. MUNSON, OF PLAINFIELD, NEW JERSEY, ASSIGNOR TO THE WOOD NEWS-PAPER MACHINERY CORPORATION, OF NEW YORK, N. Y., A CORPORATION OF VIRGINIA

FOUNTAIN CONSTRUCTION FOR PRINTING PRESSES

Application filed November 8, 1930. Serial No. 494,211.

The present invention relates to ink fountains for printing presses and has for an object to provide a novel structure which will be more compact and economical than any heretofore in use.

In the usual fountain construction, the fountain roll is mounted in a bowl carried by a pair of hinged arms spring-pressed against adjustable stops whereby the spacing between the fountain roll and the pick up roll may be regulated. Because the bowl is mounted on movable supports, flexible conduits or pipes with flexible joints must be provided for feeding the ink thereinto.

It is an object of the present invention to provide a fixed fountain bowl or basin with a resilient mounting for the fountain roll therein. By using a fixed basin, flexible pipes and fittings may be dispensed with, thereby reducing expense and overcoming the possibility of leakage.

Another object of the invention is to form the fixed basin as an integral part of the bed plate of the press. This not only dispenses with the cost of a separate bowl but provides a much more compact structure and a stiffer fountain, because the spring seated fountain roll with its brackets is mounted directly on the bed plate. Heretofore, the bowls have had to be mounted above the base plate, but by forming a depression in the bed plate to serve as a bowl, the over all height of the press is reduced and there is a corresponding saving in weight and cost of metal in the frame work of the press.

Another object of the invention is to provide a bed plate with a pair of fountain basins integrally formed therein and with a float chamber located between and in direct communication with the basins. By this arrangement the ink level in both basins will be maintained substantially constant by a single float valve and all piping will be dispensed with except the pipe that leads ink into the float chamber from a suitable source of supply.

Other objects and advantages will appear in the following description of a preferred embodiment and thereafter the novelty and

scope of the invention will be pointed out in the claims.

In the accompanying drawings;

Figure 1 is a fragmental plan view of the improved bed plate with a pair of ink basins formed therein and with a fountain roll mounted in one of the basins;

Fig. 2 is a view in section taken on the line 2-2 of Fig. 1; and

Fig. 3 is a fragmental view in section taken on the line 3-3 of Fig. 1, but showing the parts on an enlarged scale.

In the drawings, the bed plate as a whole is indicated by the reference numeral 10. The bed plate comprises a bottom wall 11 and marginal walls 12 which are preferably cored out, as shown in the drawings. On these walls is seated the frame 13 of the press, as indicated fragmentally in Figs. 2 and 3.

The enclosure formed by the marginal walls is centrally divided by a double walled transverse partition 14 to provide a pair of bowls or basins 15 and 16 respectively. In the bottom wall of the bed plate is a slot 17 which is aligned with the space between the walls of the partition and through this slot the web 18 is fed to the press. A float chamber 19 is formed in one end of the partition and ports or slots 20 and 21 lead from this chamber into the basins 15 and 16 respectively. Ink is fed into the float chamber through a pipe section 22 which passes through the bottom wall of the chamber.

The lower end of the pipe section is threaded or otherwise formed for connection to a pipe leading from the ink supply. To the upper end of the pipe section a valve 23 is mounted, this valve being provided with an operating arm 24 which at its free end carries a float 25. The float operates in the usual manner to maintain a substantially constant level of ink in the chamber 19 and hence in the basins 15 and 16.

Since the fountain mechanism in the two basins is alike, a description of the mechanism in one of the basins will suffice. Mounted in the basin 15 adjacent the partition and near opposite ends thereof are two brackets 27, finished pads 28 for these brackets being provided on the floor of the basin.

Hinged to the brackets is a pair of arms 29 which provide bearings 30 for a fountain roll 31. The free end of each arm bears upon a coil spring 32 which embraces a stud 33 fixed to and rising from the bottom wall 11. The stud passes through an aperture in the arm and is threaded near its upper end to receive a nut 34. The latter serves as a stop to limit the extent to which the roll can be raised. The upper end of the stud is supported in a bracket 35. The fountain roll may be adjusted vertically by turning the nuts 34 and to this end each nut is formed with spiral teeth meshing with a spiral pinion 37 fixed to a shaft 38 journaled in the bracket 35. Each shaft 38 is formed with a squared end 39 for the application of a wrench. Obviously, by this arrangement a very close adjustment can be made of the spacing between the fountain roll and a pick up roll 40 mounted thereabove.

The fountain roll is formed at each end with studs 41 which pass through the bearings 30 and enter pockets 42 formed in the arms 29. In each pocket and fixed to the stud is a gear 43 which meshes with a pinion 44 (Fig. 3) secured on a drive shaft 45, by which means the fountain roll is driven. Each arm 29 is formed with a bearing face 46 of somewhat larger diameter than the fountain roll but cut away to clear the pick up roll. This face is adapted to bear against the adjacent end of the fountain roll, and in order to keep the bearing faces in contact with the roll the arms 29 are laterally adjustable, being provided with set screws 47 which bear against finished surfaces or pads 48 formed on the end walls of the basin. The fountain roll 31 is provided with the usual means for controlling the film of ink thereon, such means constituting a blade 50 carried by a head 51 hinged upon the brackets 27. The usual means 52 are provided for adjusting the blade so as to regulate the thickness of the ink film at any point along the roll. The fountain roll in the basin 16 is indicated fragmentally in broken lines at 31a in Fig. 1.

The operation of the apparatus needs no explanation because it follows the usual practice except that the bowl or basin is stationary and the fountain roll with the mechanism for regulating the ink film is mounted in and adjustable with respect to the basin. Since the float chamber is located between the two basins 15 and 16 and communicates directly therewith through the ports 20 and 21 all flexible piping is dispensed with and the only piping necessary is that connecting the fixed section 22 with the source of ink supply.

While I have described a preferred embodiment of my invention, I wish it to be understood that this is to be taken as illustrative and not limitative, and that I am free

to make such changes in form, construction and arrangement of parts as fall within the spirit and scope of the following claims.

I claim:

1. A bed plate adapted to support the frame of a printing press, said bed plate being formed with a recess adapted to serve as a fountain bowl. 70
2. A bed plate for a printing press, said bed plate being formed with a recess adapted 75 to serve as a fountain bowl, and means for maintaining a substantially constant level of ink therein.
3. A bed plate adapted to support the frame of a printing press, and a fountain bowl integral therewith. 80
4. A bed plate for a printing press, a fountain bowl integral therewith, and means for maintaining a substantially constant level of ink therein. 85
5. A bed plate for a printing press, said bed plate being formed with a pair of recesses adapted to serve as fountain bowls, and means common to both of said bowls for maintaining a substantially constant level of ink therein. 90
6. A bed plate for a printing press, said bed plate being formed with a pair of recesses adapted to serve as fountain bowls, said bed plate being also formed with a float chamber between said bowls and in communication therewith, and means in the float chamber for maintaining a substantially constant level of ink in each bowl. 95
7. A bed plate for a printing press, a pair of fountain bowls integral therewith, and means between the bowls and directly connected therewith for maintaining a substantially constant level of ink in the bowls. 100
8. In a printing press a fixed bowl, a fountain roll mounted therein, a pick-up roll mounted above the fountain roll, means for adjusting the position of the fountain roll with respect to the pick-up roll, a float chamber integrally connected to and communicating with said bowl, and means in the float chamber for maintaining a substantially constant level of ink in the bowl. 105
9. In a printing press a pair of fixed bowls, a fountain roll mounted in each bowl, means for adjusting each roll vertically, a fixed float chamber between said bowls and communicating therewith, and means in the float chamber for maintaining a substantially constant level of ink in the bowls. 110
10. A bed plate for a printing press formed with a pair of recesses each adapted to serve as a fountain bowl and also formed with a slot between the bowls to pass a web to the press, said bed plate being further formed with a float chamber at one end of the slot and with ports connecting the float chamber with the bowl respectively, and means in the float chamber for maintaining a substantially constant level of ink in the bowls. 115
11. In a printing press a fixed bowl, a pair 120
12. In a printing press a fixed bowl, a pair 125
13. In a printing press a fixed bowl, a pair 130

of arms mounted in the bowl, a fountain roll supported by the arms, means for adjusting the arms with respect to the bowl, and means for maintaining a substantially constant level of ink in the bowl.

- 5 12. A bed plate for a printing press formed with a recess adapted to serve as a fountain bowl, a pair of arms mounted in the bowl, means for adjusting the arms vertically with respect to the bowl, a fountain roll journaled in the arms, each arm being formed with a bearing face adapted to bear against the adjacent end of the roll, and thrust means for holding said bearing faces against the roll.
- 10 13. A bed plate for a printing press formed with a recess adapted to serve as a fountain bowl, a pair of arms mounted in the bowl, means for adjusting the arms vertically with respect to the bowl, a fountain roll journaled in the arms, each arm being formed with a bearing face adapted to bear against the adjacent end of the roll, and a set screw on each arm, the bowl being formed with finished surfaces at each end against which the set screws are adjustable to hold said bearing faces against the ends of the roll.
- 15
- 20
- 25

In testimony whereof, I have signed this specification.
